Primary Examiner—Ian Simmons*Assistant Examiner*—Carla Wright(74) Attorney, Agent, or Firm—Robert D. McCutcheon(57) CLAIM

The ornamental design for a hand-held wireless device, as shown and described.

DESCRIPTION

FIG. 1 is a top right perspective view of a hand-held wireless device showing our new design;

FIG. 2 is a top left perspective view thereof;

FIG. 3 is a bottom perspective view thereof;

FIG. 4 is a top plan view thereof;

FIG. 5 is a bottom plan view thereof;

FIG. 6 is a front elevation view thereof;

FIG. 7 is a left side elevation view thereof;

FIG. 8 is a rear elevation view thereof; and,

FIG. 9 is a right side elevation view thereof.

The broken line showing of environmental structures is for illustrative purposes only and forms no part of the claimed design
